UNITED STATES PATENT OFFICE.

JAMES JACQUES AND CLARENCE S. TRASK, OF LOWELL, MASSACHUSETTS, ASSIGNORS TO THE COLUMBIA CASH REGISTER COMPANY, OF PORTLAND, MAINE.

CASH REGISTER AND INDICATOR.

SPECIFICATION forming part of Letters Patent No. 568,764, dated October 6, 1896.

Application filed July 19, 1895. Serial No. 556,474. (No model.)

To all whom it may concern:

Be it known that we, JAMES JACQUES and CLARENCE S. TRASK, citizens of the United States, residing at Lowell, in the county of 5 Middlesex and Commonwealth of Massachusetts, have invented a certain new and useful Improvement in Cash Registers and Indicators, of which the following is a specification.

Our invention relates to cash registers and 10 indicators; and it consists in the devices and combinations hereinafter described and claimed.

Said invention comprises key-coupling devices, means of preventing the return movement of any key until its operative movement is completed, means of preventing over-registration, means of preventing the simultaneous operation of two keys of the same section, means of preventing any section of 15 the register and indicator being operated after another section has begun to be operated, means of preventing the drawer from being opened until the key has completed its operation and returned to its normal position, 20 means of releasing the indicating-tablets, and 25 means of resetting the registering-wheels.

In the accompanying drawings, on four sheets, Figure 1 is a side elevation of the lower part of the case and the frame and operative parts, the side and upper part of the case being removed; Fig. 2, a vertical section on the line 2 2 in Fig. 3 of the machine and parts of the case and drawer, the lower part of the case near the front of the same being 30 in right end elevation; Fig. 3, a plan of the machine, omitting the case; Fig. 4, an isometric perspective view of a key-stop; Fig. 5, a plan of keys, key-stops, the registering-segment and its shaft, and one of the pawl-levers which prevent over-registration; Fig. 6, 35 a front elevation of the parts shown in Fig. 5 and the dog-plate, its spring, and operating-slide; Fig. 7, a plan of the drawer-locking lever; Fig. 8, a side elevation of one of the registering-wheels, its actuating and stop pawls, stop-pinion, and one of the resetting-dogs, one of the springs which draw the resetting-plate toward the registering-wheels, 40 said plate and the shafts of said gear and pinion being in section; Fig. 9, a plan of the 45

registering-wheel, its gear and ratchet, said gear being broken away to show its pawls; Fig. 10, a side elevation of the resetting-lever as arranged at the right of the machine; Figs. 11 and 12, elevations, respectively, of a key-slide and key-stop and of a pivoted key and key-stop. 55

A is the case, of usual form, having a lower compartment *a*, in which is arranged a drawer *B*, forced outward in the usual manner by a spring *b*, secured to the inside of the back of said lower compartment. 60

All the mechanism of the register and indicator is supported in a frame *C*, which rests upon the top of said compartment *a* within 65 the upper compartment *a'* of the case *A*.

Each key *D* consists of a bent lever, pivoted at its upper end on a fulcrum-rod *d*, which extends the whole length of the machine and is common to all the keys, substantially as 70 shown in a previous application, Serial No. 472,476, by said Jacques, May 1, 1893, and now pending, and the slides *D'* are pivoted to the lower rear corners of said keys at *d'* and are given a longitudinal backward movement by the depression of the buttons *d''* of 75 said keys, substantially as shown in said previous application and in an obvious manner. The slides *D'* are each provided with a laterally-projecting pin *d'''*, which strikes the 80 front down-hanging arm *i* of the corresponding signal-raising lever *I* and causes the rear arm of said lever *I* to raise the corresponding signal-rod *h* and signal *H*, as shown in a former patent to said Jacques, No. 480,698, 85 dated August 9, 1892, and said signals and signal-rods are guided vertically by horizontal guides *cc'*, and when raised are supported, as shown in said patent, by a sliding locking-rod *J*, drawn by a spring *j* (instead of by a 90 weighted lever, as shown in said patent) in a well-known manner in one direction, to engage and hold up said signal-rods, each signal-rod having a shoulder *h'*, which rests upon said locking-rod when said signal-rod 95 is in its raised position, and there being as many locking-rods as there are sections of the machine or denominations of money to be indicated and registered thereby.

On a shaft *J'*, common to all the sections and 100

parallel with the locking-rod J, are fast the ratchet-wheel J² and the side ratchet-wheels J', (there being one wheel J' in each section,) each of said ratchet-wheels having the same number of teeth. A pawl J³, Figs. 1, 2, and 3, engages the ratchet-wheel J² and is pivoted on a horizontal rod j⁴ supported on the nearly vertical bars f of the swinging frame F, said bars f being pivoted loosely on the fulcrum-rod d above named and being connected near their lower ends by another horizontal rod f', which extends back of all the keys D. Said frame F is swung backward by the operation of any key, carrying backward said pawl J³ and causing the ratchet-wheel J² and each of said wheels J' to revolve an angular distance measured by a single tooth and causing a single tooth of each wheel J' to run over the arm j', rigidly secured to the corresponding locking-rod J and moving said locking-rod to the left sufficiently to release all the previously-supported signals, said locking-rod being immediately moved in the other direction by the spring j to engage the newly-raised signal-rods.

The releasing operation of any side ratchet-wheel J takes place during the first quarter of its movement, so that when the locking-rod is in sections and the key-coupling device hereinafter described is omitted, a key in one section or a key in each of two sections may be partly operated, with the effect of dropping all the previously-exposed signals, and then a key in the remaining section may be fully operated, displaying a signal corresponding to said last-named fully-operated key, and the operation of the partly-operated key or keys may, without dropping said last-named signal, be completed, raising the corresponding signals and completing the proper registration.

Each key-slide D' is provided with an upward extension d⁴, on which is pivoted a coupling-lever d⁵, the same being substantially as shown in Figs. 1 to 3, and having a down-hanging arm d⁶, the lower end of which normally bears against the back side of the front e² of the frame C, holding up the long arm d⁷ of said lever d⁵, but as the key-slide is pushed slightly backward said long heavier upper arm d⁷ falls and a notch d⁸, with which the under side of said arm d⁷ is provided, engages a horizontal key-coupling and key-controlling rod E, which extends from side to side of the machine and is supported at its ends in two horizontal rack-bars E', which slide on studs e' e², passing through horizontal longitudinal slots e³ e⁴ in said rack-bars. The front ends of the rack-bars E' are pivoted at e⁵ to the side bars f of the frame F, so that the operation of any key D pushes said rack-bars backward and causes all the key-slides D', which have moved backward far enough to allow the coupling-levers d⁵ to engage the coupling-rod E, to complete their operative movement and to make their move-

ment in unison with each other, so that after two or more of the coupling-levers have engaged said rod E the complete movement of all the corresponding keys is insured by a complete movement of one of said keys, thus enabling a person simultaneously to operate a key in each section of the machine by the use of one hand.

Where the coupling devices above described are used, a single locking-rod extending over all the sections of the machine may be used instead of the sectional locking-rod above described.

Each rack-bar E' is provided on its upper surface with a rack e, Fig. 1, adapted to be engaged alternately by two pawls e⁷ e⁸, pivoted at e⁹ e¹⁰ on the frame C, said pawls being connected to each other by means of a shift-lever e¹¹, also pivoted midway between its ends on said frame, said lever e¹¹ having slots e¹⁹ e²⁰, through which studs e¹¹ e¹² on said pawls, respectively, loosely project, so that turning said lever e¹¹ will engage one of said pawls with and disengage the other from said rack e. Said lever e¹¹ has an upwardly-extending weighted arm e¹³ to overbalance said lever and hold either of said pawls in engagement with said rack.

At each end of each rack e is an upward projection e¹⁴ e¹⁵, which strikes against the under side of the free end of the corresponding pawl e⁷ e⁸ and lifts it out of engagement with said rack. The front pawl e⁷ when in engagement with said rack prevents the return movement of the rack-bar and of the keys coupled thereto until the operative or backward movement of said rack-bar and coupled keys is substantially completed, but just at the completion of said operative movement said front pawl e⁷ is lifted by the front projection e¹⁴, rocking the lever e¹¹ and throwing the rear pawl e⁸ into engagement with said rack, where it remains until the return movement is completed, said return movement being caused by the contraction of springs F', each rack-bar and each key-slide being connected by a helical spring F' to a plate F² rigidly to the bottom of the front of the frame C, Figs. 1 and 2. At the completion of the return movement of the rack-bar and coupled keys the pawl e⁸ is raised by the projection e¹⁵, causing the pawl e⁷ to fall again into engagement with said rack e.

The simultaneous backward movement of two key-slides in the same section of the machine is prevented by the key-stops G, Figs. 2 and 4, the same being blocks which nearly fill the spaces between the upright parts e⁶ of the frame C, which form the ends and the divisions between the sections of the machine, which is represented in Fig. 3 as having three sections and four uprights, the combined lateral thickness of a series of key-stops of a single section being such as to leave room for only one key-slide D' to pass through said series. The rear ends of the key-slides are beveled to a vertical edge d⁹, and the front

side corners of the key-stops are correspondingly beveled at g to allow said key-slides to enter readily between adjacent key-stops, as shown in Fig. 5 and as shown in the Patent 5 No. 537,086, granted to said Trask April 9, 1895. In the last-named patent the key-stops slide upon two parallel supporting and guiding rods, between which the rear ends of the key-slides enter, said rods lying in a plane 10 at right angles to that in which the key-stops lie. The guide-rods $g' g^2$ are herein represented as lying in the same plane as that of the longitudinal axes of the key-slides, (see Figs. 2 and 5,) and the rear end of each key- 15 slide is forked at d^{10} , as shown in Fig. 1, in such a manner as to separate the key-stops equally above and below said supporting and guiding rods, the stops being very loose on the rear rod g^2 , which serves merely to keep 20 said stops from turning on the rod g' , two rods being used on account of the angular shape of the stops, but if the stops were round, as shown in said previous patent to said Jacques, a single supporting-rod would be 25 sufficient, each stop in that case being beveled on each side and all around and being allowed to revolve freely on its supporting-rod, as represented in Figs. 11 and 12, which show, respectively, disk-shaped stops in connection with a forked key-slide and such stops in connection with a forked pivoted key-lever D^2 of otherwise ordinary construction, the purpose being in each case to separate 30 said stops equally on opposite sides of the supporting-rod and thus prevent said stops from canting and binding on said rod. The key-slides are guided in front and rear guide-plates $c^2 c^3$. Each of the key-slides is notched on the under side at d^{11} to receive a 35 key-locking plate L , which extends across the machine, Figs. 1, 2, and 6, in front of the guide-plate c^2 , and is provided with vertical slots l , through which cap-screws l' are driven into said front guide-plate. The plate L is 40 normally held out of engagement with the notches d^{11} by gravity and by the contractile power of springs l^2 , connected to said plate L and to the plate F^2 above named, but is raised 45 into the notches d^{11} of all keys not operated 50 when the rack-bars E are moved backward, said plate L having end studs l^3 , which project into or through slots e^{10} in said rack-bars, which slots are parallel with the slots $e^3 e^4$ above described nearly throughout their 55 entire length, but at their rear ends said slots e^{10} are inclined slightly downward at e^{17} , so that, the studs l^3 being normally in the rear ends of said slots e^{10} , said plate L is raised by the backward movement of said rack-bars 60 into said notches d^{11} and prevents the movement of a key-slide in any section after a key-slide of any other section has begun to be operated.

The under side of the slides is cut away to 65 the depth of the notch d^{11} at d^{12} , just in front of said notch, in order that the operated keys may not prevent the raising of said plate L .

When the keys and rack-bars return to position, the plate L is forced down out of the notches d^{11} by the inclination e^{17} of the slot e^{16} . 70

The initial registering-gear K in each section of the machine is driven by a segment M of a gear, substantially as in said pending application of said Jacques, that is, the segment-arm m turns on a fixed shaft m' and is 75 connected by rods $m^2 m^3$, parallel with the shaft m' , to a shorter arm m^4 , (which, with the rod m^2 , merely serves to stiffen and steady the arm m and lower rod m^3 ,) said lower rod m^3 extending over all the key-slides in the 80 same section and at right angles therewith, and each key-slide having an upwardly-extending stud d^{13} , which, in the operation of said key-slide, strikes and pushes backward said rod m^3 and rocks the arm m , causing the 85 gear K to make a part of a revolution, said studs being at such different distances from said rod m^3 that said last-named rod and the segment M will be swung an angular distance proportioned to the number on the key by 90 which such movement is effected, and the gear K , engaged by said segment and having (in a machine for registering money of a decimal system) ten teeth or a multiple of ten teeth, (twenty such teeth being shown in 95 the drawings,) will be turned by the complete operation of any key the number of tenths of a revolution indicated by the number on the button of the key.

The operative motion of the gear K is communicated to the pinion n of the first-numbered registering-wheel N by a ratchet-toothed clutch O , arranged concentrically with said gear and numbered wheel, one counterpart o of said clutch being fast on 100 said gear and the other counterpart o' being fast on said pinion n , and said clutch counterparts being held in engagement with each other by a helical spring T , which surrounds the shaft and is compressed between said 105 gear K and the adjacent upright c^4 of the machine, so that turning the gear K in one direction by the operative or forward movement of the segment M partially rotates said pinion n , while turning said gear K in the other 110 direction (by the return movement of the segment M , caused by the contraction of the helical spring T , connecting the frame C and the arm m of said segment M , as shown in Fig. 1) produces no effect on said pinion n , 115 the teeth of the counterpart o sliding over the teeth of the counterpart o' .

The wheel N in each section of the machine (three sections being represented in Fig. 3) has a hub n^5 , having ten ratchet-teeth 120 n^6 , some one of which is always in engagement with a pawl n^7 , pivoted on the pinion n , so that said pinion n and wheel N are for registering purposes but a single wheel, each being loose on a shaft P , which extends 125 through every section of the machine and supports all the gears K and all the numbered registering-wheels and their pinions, Figs. 1, 2, 3, 8, and 9.

The periphery of each wheel N is numbered from "1" to "0" at equal intervals, and in each section of the machine the numbered wheels N N' N² N³ N⁴ are duplicates of each other and the pinions n n' n² n³ n⁴ are also precisely alike, (except that only the first pinion of each series is provided with a clutch counterpart o',) each of said pinions carrying a pawl n⁵ to engage a tooth n⁶ on the corresponding numbered wheel, as above described. When any numbered wheel (except the one at the extreme left of a series) makes a complete revolution, the numbered wheel next at the left makes one-tenth of a revolution, caused by an intermediate stop-pinion n¹⁰ n¹¹ n¹² n¹³, (represented as having eight teeth n⁸ and four stop-surfaces n⁹,) one of said stop-surfaces normally resting against the periphery of a numbered wheel, while its teeth engage the pinion n', n², n³, or n⁴ of the numbered wheel next to the left. Each numbered wheel has a lateral projection, as shown at the left or dollar-section in Fig. 3, or double tooth n¹¹, which once in every revolution of said numbered wheel turns the stop-pinion next to the left an angular distance measured by two teeth or one stop-surface of said pinion, a notch n¹³, with which said numbered wheel is provided, admitting the projection or corner formed by two adjacent stop-surfaces to allow of such turning.

The described construction of the stop-pinions requires that the pinion n should have twenty teeth in a decimal system. When it is desired to reset the registering-wheels to their "0" positions, the shaft P, Figs. 1, 2, 3, 8, 9, and 10, on which said wheels are loose, is given a complete revolution, said shaft having a longitudinal groove p, which when the registering-wheels are in their "0" positions and said shaft P is in its normal position is engaged by other pawls p', one of said pawls being pivoted on each registering-wheel and pressed against said shaft P by a spring p². A hub p³ is rigidly secured on said shaft P and is provided with a projection p⁴, to which is secured a spring arm p⁵, which normally rests on a horizontal stud c⁵, fixed in the frame C, and is held against said stud by a spiral spring p⁶, which surrounds the shaft P, Fig. 3, and has one end p⁷, which engages said frame C, and another which engages said arm p⁵.

A slide Q, drawn by springs q⁵ toward the shaft P, extends throughout the machine parallel with said shaft and supporting in each section of the machine as many sliding dogs q q' q² q³ q⁴ as there are numbered registering-wheels, each such dog being forced radially toward said shaft P and wheels by springs q⁶ and being held to said slide Q by cap-screws q⁷, which pass through slots q⁸ into said slide. Said sliding dogs are normally held out of engagement with the registering-wheels by the projecting parts p⁸ or cams on the hubs of the shaft P, but when the shaft is turned (which is accomplished by pulling the spring-arm p⁵

laterally until it clears the supporting-stud c⁵, when the shaft may be turned by using said arm p⁵ as a lever or automatically by the spring p⁶) said cams move out of the way of the slide Q and allow the sliding dogs to bear upon the numbered wheels and to stop said wheels by entering the notches n¹³ when said wheels reach their "0" positions. After said wheels are reset the shaft is turned once in the reverse direction, disengaging the sliding dogs from said wheels, and the arm p⁵ is slipped over the stud c⁵. The numbered wheels are thus adjusted without moving their pinions or drawing the intermediate stop-wheels out of engagement with said pinions.

The segment M, Figs. 1, 2, 3, and 5, is provided with two racks m⁵ m⁶, having teeth inclined in opposite directions, and two pawls m⁷ m⁸ are pivoted on the frame C at c⁷ c⁸ and arranged alternately to engage said racks, said pawls being connected by a lever m⁹ of the first order, having slots m¹⁰, which are engaged by pins m¹¹ m¹², which project laterally from said pawls near the free ends of the same, respectively. The rear end of the lever m⁹ is connected by a rod R to the front end of the shift-lever e⁸, above described, so that when a rack-bar is moving backward and its return or forward movement is prevented by the pawl e⁷, as above described, the return or backward movement of the segment M is prevented by the pawl m⁸, engaging the rack m⁶, and when the rack-bar completes its movement and the pawl e⁸ becomes engaged with the rack e the pawl m⁷ is simultaneously engaged with the rack m⁵. The pawl m⁷ is weighted at m¹³ to counterbalance the weight of the connecting-rod R.

A pawl-lever S in each section of the machine turns on a horizontal rod s, supported in the frame C, and has a broad lower arm s', adapted to be struck by the operative or backward movement of any key-slide in the same section, causing a tooth s² at the upper end of said lever S to engage the first registering-pinion N of the corresponding series just as said operative movement of said slide is completed, to prevent said pinion being carried too far by its own momentum and that of the attached clutch counterpart o', Figs. 1, 2, and 3.

A rod b' connects the side bars f of the swinging frame F and has an arm b², which extends backward near the middle of the machine and which at its rear end is jointed at b³ to the upper end of a lever b⁴, shaped like an inverted T and pivoted between its lower ends on the frame. To each of the lower ends of said lever b⁴ is pivoted a bolt b⁵, b⁶, the bolt b⁵ being beveled at its lower end and being provided with a slot b⁷, through which its pivot b⁸ passes into the lever b⁴, enabling said bolt to rise on said lever when the drawer B is pushed into the case. When any key is operated, the bolt b⁵ is raised by the action of the lever b⁴ out of the notch b⁹ in a central partition in the drawer B, and

5 said drawer is pushed by the spring b under said bolt b^5 , and at the same time the bolt b^6 is pushed down into another notch b^{10} in said partition, (the lower end of said bolt b^6 being beveled to allow its lower rear edge b^{11} to engage said last-named notch readily,) preventing the drawer from opening farther until the return movement of the key is nearly completed, when the rear bolt b^6 is likewise 10 disengaged from its notch b^{10} , allowing the drawer to spring open. This construction prevents the drawer from being opened by a partial operation of the key.

We claim as our invention—

15 1. The combination of a series of key-slides, bars, movable with any of said key-slides, and each provided with a rack, a pair of oppositely-acting pawls for each of said racks, and a lever, connecting the pawls of a pair to 20 each other and arranged to hold one of said pawls in engagement with the corresponding rack when the other is out of such engagement, and said bars having also projections each adapted to raise a pawl out of engagement 25 with the corresponding rack at the completion of the movement of the corresponding bar in one direction, the registering-gear, a segment of a gear, engaging said gear and operated by the movement of any key-slide 30 to rotate said gear, said segment having two racks, provided with oppositely-inclined teeth, two pawls, adapted to engage said last-named racks, respectively, a lever, connecting said last-named pawls to each other and 35 adapted to hold either of said last-named pawls out of engagement with the corresponding rack when the other is in such engagement, and a rod, connecting said levers, to cause the operative movement of said seg- 40 ment to end with the operative movement of the corresponding key-slide and to prevent said segment from moving in one direction until its movement in the opposite direction is completed, as and for the purpose specified.

45 2. The combination of a series of keys, a

series of stops and a guide-rod passing through said stops and arranged at right angles to the planes in which said keys move, said keys having forks adapted to pass between said stops on opposite sides of said 50 guide-rod, as and for the purpose specified.

3. The combination of the case, the keys, the drawer, sliding in said case and having two notches, a spring, to open said drawer, a lever, operated by the movement of any key, 55 two bolts, pivoted to said lever on opposite sides of its fulerum, one of said bolts being normally engaged with one of said notches when said drawer is closed and withdrawn therefrom at the beginning of the operative 60 movement of any key and supported on the top of said drawer, on a slight outward movement of said drawer, and the other of said bolts being thrown into engagement with the other of said notches, and withdrawn there- 65 from on the completion of the return movement of said key, to prevent said drawer being opened until said key is fully operated and returned to its normal position, as and for the purpose specified. 70

4. The combination of the frame, a shaft, having a longitudinal groove, a series of registering-wheels, loose on said shaft, an equal series of pawls, each pivoted on one of said wheels and each bearing upon said shaft and adapted to engage said groove, a spring-arm, secured to said shaft, a stud, on said frame, to stop said arm, and another spring, to rotate said shaft when said arm is disengaged from said stud until said arm again strikes 80 said stud, to restore said wheels to their zero positions, as and for the purpose specified. 75

In witness whereof we have signed this specification, in the presence of two attesting witnesses, this 15th day of June, A. D. 1895. 85
